UNITED STATES PATENT OFFICE.

FRANK A. LEIB, OF SANTA CLARA COUNTY, CALIFORNIA.

RELEASING ATTACHMENT FOR ELECTRIC STARTING MOTORS.

Application filed February 23, 1927. Serial No. 170,083.

This invention relates to an electric starting motor for automobiles and the like which serves the function of rotating or cranking the engine crank shaft when starting and 5 particularly to that type of starting motor in which a Bendix drive is employed.

Electric starting motors employing a Bendix drive are equipped with a driving pinion which is automatically and quickly shifted 10 along the shaft of the starting motor into mesh with the teeth on the flywheel of the engine when a circuit is closed through the starting motor. The pinion remains in mesh with the flywheel gear and, accordingly, performs the operation of cranking until the 15 engine commences to fire, when the direction of drive is reversed and the pinion is automatically shifted out of mesh and released. The teeth of both the flywheel and pinion are 20 beveled on the entering side for easy engagement, but the beveled ends of the gears wear, chip and break in time from frequent use. When this happens trouble begins as it becomes difficult to mesh the gears. In some 25 instances, the gears become jammed and the only thing the driver can do is to move the transmission gears into direct drive and then rock the car back and forth until the starter gears accidentally release. This is fairly 30 easily accomplished, particularly, if the car is standing on a grade, but it becomes difficult and sometimes almost impossible to accomplish if the automobile is standing on soft ground or if the driver is alone and cannot impart sufficient momentum to the car. In such instances it often becomes necessary 35 to call a garage man or to wait until assistance can be obtained.

The object of the present invention is to 40 generally improve and simplify the construction and operation of starting motors of the character described and particularly to provide an extension on one or both ends of the starting motor shaft whereby the shaft may 45 be manually engaged and rotated in a reverse direction to release the gears when they become jammed. The invention is shown by way of illustration in the accompanying drawing which is a side elevation of a starting motor, said view being shown partly in 50 section and also disclosing the extensions on the starting shaft whereby the shaft may be manually engaged and rotated.

Referring to the drawing, A indicates the 55 starting motor; B the shaft driven thereby; C the driving pinion and D the flywheel gear.

The general construction disclosed is a modern type of Bendix automatic gear shift and is, accordingly, equipped with a starting switch E, a coarse threaded sleeve F and a 60 spring connection G which allows a certain amount of flexibility and prevents too sudden application of the gears.

In actual operation when the starting button of the switch E is pressed down, the connections are made between the storage battery and the starting motor. This causes the armature and the starter shaft B to rotate rapidly, thereby causing the driving pinion C to travel towards the motor on the coarse 65 threaded sleeve F and to mesh with the gear D on the flywheel. As soon as the pinion C is fully engaged with the flywheel gear D it comes up against a stop and is firmly locked about the coarsely threaded sleeve thus 70 rotating with the starting motor and shaft and allowing the starting motor to crank the engine. When the engine starts under its own power and the starting switch is released, the pinion C is automatically thrown out of 75 mesh with the flywheel gear and the starting motor and shaft comes to rest. The teeth of both the pinion and the flywheel are bevelled, as previously stated, on the entering side for 80 easy engagement, but the bevelled ends gradually wear, chip and break due to constant use and it is then that trouble commences as it becomes difficult to mesh the gears and it often happens that the gears jam tightly, thus rendering the starting motor inoperable. In the present instance, release of the 85 gears may be readily and quickly accomplished with a minimum effort or trouble by merely providing an extension on one or both 90 ends of the starter shaft. This may be accomplished by extending the end of the starter shaft as shown at 2 and forming flat faces thereon so that the end of the shaft may be gripped by a wrench or the like and manually rotated. It is, of course, rotated in the 95 direction opposite to that of the starting motor and the coarse threaded sleeve will, during such reverse rotation automatically retract the pinion and will thus break the interlock between the gears.

In some automobiles, one end of the starter shaft is more accessible than the other. If this is the case, a hole may be drilled in the end of the motor housing, as indicated at 3. The end of the armature or starter shaft is 100 also drilled and tapped and a bolt is inserted as indicated at 4. This is permanently 105

screwed into place and it thus serves as a projection which may be engaged by a wrench to manually rotate the armature or starting shaft whenever a jam occurs. Where the 5 end of the motor housing is drilled to permit insertion of the bolt as illustrated, it is preferable to apply a dust cap as indicated at 6 to prevent admission of dust and grit. The device is exceedingly simple and may be attached to the motors as manufactured and sent out by the factory or it may be attached to any Bendix drive by garage men or mechanics by merely drilling the end of the motor housing and inserting the bolt as previously 10 stated, or by inserting a bolt in the opposite end of the shaft indicated at 2. If the arrangement is applied at the factory it is merely necessary to extend the ends of the shaft and to form flattened surfaces thereon 15 which may be gripped by a wrench. The whole device is, accordingly, exceedingly simple and may be attached at a comparatively small cost.

While certain features of the present invention are more or less specifically described, I 20 wish it understood that various changes may be resorted to within the scope of the appended claims. Similarly that the materials and finishes of the several parts employed 25 may be such as the manufacturer may decide or varying conditions or uses may demand.

Having thus described my invention, what I claim and desire to secure by Letters Patent is:—

1. In a starter motor of the character described, a motor, a starter shaft extending from one end of the motor and provided at the other end interiorly of the motor casing with a threaded socket, and a screw extending into the motor casing and engaging the threads of the socket and rigid with the starter shaft, said screw being provided exteriorly of the motor casing with a polygonal head adapted to be gripped by a wrench to manually rotate the shaft in a reverse direction. 35
2. In a starter motor of the character described, a motor, a starter shaft extending from one end of the motor and provided at the other end interiorly of the motor casing with a threaded socket, and a screw extending into the motor casing and engaging the threads of the socket and rigid with the starter shaft, said screw being provided exteriorly of the motor casing with a polygonal head 40 adapted to be gripped by a wrench to manually rotate the shaft in a reverse direction, said starter shaft being provided at its extended end with an integral polygonal projection also adapted to receive a wrench for 45 rotating the starter shaft manually. 50
